[57] ABSTRACT

An apparatus for withdrawing or sucking off rapidly moving yarn material comprising a suction bore, an approximately cylindrical compartment into which the suction bore opens approximately coaxially and which possesses a larger diameter relative thereto. A compressed air channel opens into the cylindrical compartment. The compressed air channel enters approximately tangentially into such cylindrical compartment.

APPARATUS FOR WITHDRAWING RAPIDLY MOVING YARN MATERIAL

BACKGROUND OF THE INVENTION

The present invention relates to a new and improved construction of apparatus for sucking off or withdrawing rapidly moving yarn material. The term "yarn material" as used in the context of this application is not employed in any limiting sense, rather is intended to encompass most types of filamentary material, such as threads, yarns, and the like.

The prior art is familiar with equipment for sucking off rapidly moving yarn material which functions according to the principles of an injector. To this end there is provided a suction conduit guiding the yarn, the suction conduit opening into a widened cylindrical compartment and is surrounded by a ring-shaped discharge or jet nozzle which flow communicates with a compressed air source. Compressed air is delivered by means of a radially extending channel into the annular compartment opening at the jet nozzle.

Equipment of this type enables the sucking off or withdrawal of yarns travelling at speeds exceeding 3,500 m/min. Yet, such type state-of-the-art equipment only produces a relatively slight tensional force. Hence, it can be only successfully employed in those situations where the yarn is sucked off without practically any deflection and where there is no danger that the yarn will become caught at rotating components owing to the absence of a sufficient pulling or tensile load.

SUMMARY OF THE INVENTION

Hence, from what has been explained above, it should be recognized that this particular field of technology is still in need of equipment for withdrawing or sucking off rapidly moving yarn material in a manner not associated with the aforementioned drawbacks and limitations of the heretofore discussed proposals of the prior art. It is therefore a primary object of the present invention to provide apparatus suitable for this purpose which successfully and reliably fulfills the existing need in the art.

Still a further significant object of the present invention relates to an improved apparatus for sucking off rapidly moving yarn material which is capable of exerting a sufficient tension force at the yarn material.

Yet another important object of the present invention relates to an improved construction of apparatus for withdrawing rapidly moving yarn material in a highly efficient, effective, and reliable manner, while exerting sufficient tension upon the yarn material.

The inventive solution is based upon the recognition that upon introducing a yarn through the suction or sucking up conduit, this yarn will be only directly impinged to a slight degree by the high-energy jet stream of an injector mechanism and will move in the core zone, the flow velocity of which gradually increases only after experiencing a commingling action. Consequently, the solution proposed by the invention is predicated upon the features of generating a spin or twist flow in the cylindrical compartment by means of compressed air and permitting the yarn material, centrally introduced through the suction conduit, from being carried out of the core zone by the spin flow and directly subjected to the action of such spin flow.

Now, in order to implement the aforementioned objects and others which will become more readily appar-

ent as the description proceeds, and for the purpose of realizing a construction of apparatus suitable for the intended purposes, the inventive apparatus embodies a suction bore, an approximately cylindrical compartment into which approximately coaxially opens the suction bore and which compartment possesses a larger diameter than the suction bore. Further, there is provided a compressed air channel which opens into this cylindrical compartment, the compressed air channel entering approximately tangentially into the cylindrical compartment.

According to a further aspect of the invention, the position of the mouth of the compressed air channel at the cylindrical compartment with respect to the plane containing the mouth of the suction bore is offset downstream with respect to the direction of flow, i.e., also with regard to the direction of movement of the yarn material.

BRIEF DESCRIPTION OF THE DRAWING

The invention will be better understood and objects other than those set forth above, will become apparent when consideration is given to the following detailed description thereof. Such description makes reference to the annexed drawing wherein the single FIGURE illustrates in longitudinal sectional view an exemplary embodiment of inventive apparatus for withdrawing or sucking-off rapidly moving yarn material.

DETAILED DESCRIPTION OF THE PREFERRED EMBODIMENTS

Describing now the single FIGURE of the drawing, it is to be understood that the exemplary illustrated apparatus constitutes a piece of equipment intended to be installed at the winding locations or stations of a texturizing machine in which there can be randomly processed right-hand or left-hand twisted yarn. To this end reference numeral 2 designates a housing body which can be secured in any convenient manner, therefore not particularly shown, to the winding location or station. A longitudinal or lengthwise extending bore 4 completely extends through the housing body 2. Bores 6, 8 and 10 provided at the housing body 2 open into the longitudinal bore 4 in a direction substantially perpendicular thereto. The bores 6 and 8 are connected via conduits 14 and 16 with a suitable suction installation 12 constituting part of the texturizing machine. The bore 10 arranged between the bores 6 and 8 is connected via a conduit 18 with a compressed air source 20.

While the one end of the longitudinal bore 4 is closed or covered by a suitable cover member 22, an insert 24 extends into the longitudinal bore 4 from the opposite end of the housing body 2. This insert 24 embodies a sleeve member 26 which incorporates a tapered central portion 28 and a tapered end portion 30. The tapered central portion 28 together with the inner wall of the longitudinal bore 4 delimits a compartment 32 which flow communicates with the bore 10 and is sealed by means of sealing O-rings 34 inserted at both ends of the central portion 28 into the sleeve member 26, as shown. The sleeve member 26 is retained in the axial direction within the housing body 2 by means of an adjusting screw 36 which engages with a peripheral groove 38 provided at such sleeve member 26.

At the tapered end portion 30 of the sleeve member 26 there is provided an elongate hole 40 through which

extends an entrainment screw 42. The entrainment screw 42 is inserted into a gripping or operating element 44 which is displaceably guided at the tapered end portion 30. By means of the entrainment screw 42 the gripping element 44 is connected with a suction conduit or pipe 48 which is seated in a bore 46 of the sleeve member 26 and for the purpose of accommodating the end of the entrainment screw 42 is provided with a circumferential groove 54. The suction conduit 48 contains an axially extending suction bore 50 with a substantially trumpet-shaped inlet 52. The discharge mouth or outlet 58 of the suction bore 50 is located at a stepped end portion or mouthpiece 56 of the suction conduit 48. A compressed air channel 60 opens into the sleeve bore 46, this compressed air channel 60 being offset downstream in the direction of flow by a small amount with regard to the outlet or mouth 58. Moreover, the axis of the compressed air channel 60 extends approximately tangentially with regard to the wall of the sleeve bore 46.

Now, within the sleeve bore 46 the suction conduit 48 can be displaced out of its full line illustrated terminal position together with the gripping or operating element 44 into the phantom line illustrated terminal position. The extension of the elongate hole 40, limiting the displacement path, is selected such that two O-rings 62 inserted into the suction conduit 48 come to rest at both sides of the compressed air channel 60, whereas the mouth thereof is covered by the suction conduit 48 when such is located in the phantom line illustrated terminal position.

The cylindrical compartment 64 formed by the sleeve bore 46 and the discharge end or mouth 58 of the suction conduit 48 is in flow communication, through the agency of a trumpet-shaped outlet 66, with a compartment 68 bounded by the longitudinal bore 4 and the cover member 22, and into which compartment 68 the bore 8 opens.

Now if yarn, indicated by reference character F, is brought into the neighborhood of the suction conduit inlet 52, during which time the gripping or operating element and therefore also the suction conduit 48 are located in the full line illustrated terminal position, then this yarn is sucked up by a suction air current. This air flow forms in the suction bore 50 under the action of the compressed air which flows from the tangential compressed air channel 60 into the compartment 64. If the yarn F thus arrives at the compartment 64, then it is exposed to such a strong tensional force that the travelling yarn is withdrawn in a tensioned condition.

Owing to the flow prevailing in the compartments 64 and 68, the yarn F is delivered to the bore 8 and thereafter is taken over by the conduit 16 of the suction installation 12 of the equipment. Through appropriate means, well known in this particular art, there is insured that a sufficiently high transport air velocity prevails in the conduit 16 in order to avoid clogging or damming up of yarn. If the bobbin-change operation is carried out, which for instance constituted a reason for resorting to the use of the apparatus, then the yarn travelling into the apparatus is deposited in the form of a loop upon the rotating new bobbin sleeve and the yarn connection to the apparatus and namely to the suction conduit 48 is severed by any suitable and therefore not particularly illustrated cutting device. If the appropriate yarn end has been completely grasped by the apparatus, then, by displacing the operating or gripping ele-

ment 44 into the phantom line position, the infeed of compressed air from the compartment 32 can be interrupted and therefore the apparatus can be placed out of operation.

Although the apparatus as shown in the illustrated assembled position of the insert 24, is designed for operation with left-hand twisted yarns, such can be converted most simply for processing right-hand twisted yarns. To this end, the screw 36 is released to such an extent that the sleeve member 30 is freed, and the insert 24 is withdrawn out of the longitudinal bore 4. Thereafter the cover member 22 is inserted from the leftside into the longitudinal bore 4. In its place there is inserted at the right-hand side of the housing, the insert member 24 into the longitudinal bore 4 and by means of the previously loosened screw 37 such is secured in a mirror-image reversed position. In this position the bore 10 is again in flow communication with the compartment 32, whereas the compartment 64 communicates via a compartment corresponding to the compartment 68 with the bore 6 instead of with the bore 8. However, even in this position of assembly of the insert member 24 the connection to the suction installation 12 is realized through the agency of the conduit 14.

Measurements undertaken at different apparatus constructions designed according to the teachings of this invention have shown that the inventive principles have produced surprisingly high tensional forces at the running or travelling yarns, something which is desired for the disturbance-free withdrawal of yarns from the work zone of the texturizing equipment.

Measurements carried out for instance with the illustrated apparatus and with a textured yarn 30/10 denier have resulted in a tension of 5 grams with a delivery speed of 120 m/min. The apparatus was furnished with compressed air from the compressed air source at 5 atmospheres absolute pressure and there prevailed an air consumption of 250 N liters/min.

The more important dimensions of the apparatus are given by way of example hereinafter:

1. Suction conduit 48 :		
Diameter (ϕ) of the suction bore 50		3 mm
Length of the suction bore 50		50 mm
Length of the end portion 56		2 mm
2. Compartment 64 :		
Inner diameter		7 mm
Length		110 mm
Spacing of the axis of the channel 60 from the plane of the mouth 58		2 mm
Bore diameter of the channel 60		2 mm
3. Compartment 68 :		
Inner diameter		14 mm
Spacing of the axis of the bore 8 from the end of the compartment 64		24 mm
Diameter of the bore 8		10 mm

Comparative tests have shown that the inventive apparatus, in most instances, produces a considerably larger tensional force than an injection mechanism operated under the same conditions and where the compressed air channel opens into an axially directed discharge nozzle.

The higher tensional forces which prevail for the inventive apparatus are present owing to the fact that a pronounced spin or twist flow exists in the compartment 64 which subjects the yarn in the core zone thereof and coming out of the suction bore to a revolv-

ing movement, so that oscillation antinodes and nodes form thereat. At these oscillation antinodes and nodes there engage the axial components of the spin or twist flow and entrain the yarn. As previously mentioned, the yarn thus moves externally of the core zone through the compartment 64.

While there is shown and described present preferred embodiments of the invention, it is to be distinctly understood that the invention is not limited thereto, but may be otherwise variously embodied and practiced within the scope of the following claims. Accordingly,

What is claimed is:

1. An apparatus for withdrawing rapidly moving yarn material, comprising means defining a suction bore, said means defining said suction bore comprising a displaceable suction conduit, an approximately cylindrical compartment, said suction bore opening approximately coaxially into said cylindrical compartment, said cylindrical compartment possessing a diameter which is larger than the diameter of the suction bore, a compressed air channel opening approximately tangentially into said cylindrical compartment, a sleeve member containing said compressed air channel, said suction conduit being displaceable between two positions within said sleeve member, and wherein in one of said positions the suction conduit closes the compressed air channel.

2. The apparatus as defined in claim 1, wherein the point of opening of the compressed air channel at the cylindrical compartment with regard to a plane containing the mouth of the suction bore is offset downstream in the direction of flow, and said point of opening defining the other position of the displaceable suc-

tion conduit.

3. The apparatus as defined in claim 1, further including a mouthpiece provided at said suction conduit and at which terminates the suction bore, said mouthpiece extending into the cylindrical compartment.

4. The apparatus as defined in claim 1, further including a suction installation and a compressed air source, a housing having means for connecting the cylindrical compartment with the suction installation and the compressed air channel with the compressed air source.

5. An apparatus for withdrawing rapidly moving yarn material, comprising means defining a suction bore, an approximately cylindrical compartment, said suction bore opening approximately coaxially into said cylindrical compartment, said cylindrical compartment possessing a diameter which is larger than the diameter of the suction bore, a compressed air channel opening approximately tangentially into said cylindrical compartment, means for shutting-off the compressed air channel, said means defining said suction bore comprises a suction conduit, a sleeve member containing said compressed air channel, said suction conduit being displaceable in said sleeve member, a suction installation and a compressed air source, a housing having means for connecting the cylindrical compartment with the suction installation and the compressed air channel with the compressed air source, and wherein the suction conduit and said sleeve member form an insert which can be selectively inserted into one of two positions in the housing.
